MULTIPLE JEWEL OLIVING MACHINE

Paul Numa Paroz, Lancaster, and George William Grisdale, Jr., Ephrata Township, Lancaster County, Pa., assignors to Hamilton Watch Company, Lancaster, Pa.

Application November 26, 1943, Serial No. 511,850

9 Claims. (Cl. 51—156)

This invention relates to an apparatus for oliving jewels and is particularly designed to handle a multiplicity of jewels at the same time.

Heretofore jewels for precision instruments such as watches, gauges, and the like, during their processing had to be handled singly, owing to the extremely hard nature of the material out of which they are made. Most watch jewels are made of synthetic sapphire or ruby and the only material which can be used to successfully cut or polish this material is diamond dust and owing to the extreme smallness of these jewels the operation is carried out on a single jewel at a time. This materially retards production and contributes to the high cost of manufactured jewels.

The term "oliving" which is not found in the English dictionary, yet may be found in the Swiss and French, is directed to the rounding of the internal bore of the jewel so as to present a single line of contact with the staff to thereby reduce friction. Inasmuch as the jewel industry is practically a new industry in the United States and there being no adequate term in the English dictionary to express this operation, the term "oliving" is used throughout the specification.

It is the object of this invention to provide an apparatus by means of which a group of jewels may be olived at one and the same operation.

It is a further object of the present invention to provide a rotating member adapted to give both rotation and lateral movement to the jewels being olived.

A further object of the present invention is to provide a holder for the jewels which can be positioned at any angle with regard to a rotating element.

A still further object of the present invention is to provide means for mounting a group of jewels in contact with a rotating member, the supporting means being adjustable to a desired position with regard to the rotating member.

It is a still further object of the present invention to provide rests at each side of the rotating member to accurately govern the distance the jewels are held from the rotating member.

It is a still further object of the present invention to provide individual adjusting means for the rests to allow the jewel supporting wire to be set on an angle with relation to the rotating member.

The invention is illustrated in the accompanying drawing in which:

Fig. 1 is a top plan view;

Fig. 2 is a side view.

Referring to the drawing, a base 1 supports standards 2 and 3 which have a shaft 4 journaled therein, a brush 5, having long brass bristles and end plates 6 and 7, fixed on said shaft and spaced from said standards by bushings 8 and 9. Pulleys 10, 11, and 12 mounted on said shaft provide means for driving the brush at different speeds from the same motor (not shown).

10 A ball 13 having a threaded rod 14 and an adjusting nut 15, is mounted in the base and supports a straight bar 16 and a spring bar 17 to provide a universal support for the jewel holder. A clamping bolt 18 bears against the spring bar 17 and is threaded through the straight bar 16 to securely clamp the bars 16 and 17 about the ball 13. A spring 19 bearing against the spring bar 17 and the clamping bolt 18 provides additional resiliency in this connection, while a handle rod 20 is used to correctly position the entire mounting.

Secured to the back of the straight bar 16 is a spring strip 21 which bears against a cross bar 22 and holds it firmly in a notch on the straight bar while an additional handle member 23 extends upward from the straight bar to permit the operator to insert and remove the cross bar 22. A pair of clamping arms 24 and 25 are pivotally mounted to the ends of the bar 22 at 26 and 27 to permit the clamping arms to be moved toward or away from each other by means of the adjustable threaded rod 27' and nut 28. Clamps 29 and 30 provided with clamping bolts 31 and 32 are carried on the clamping bars 24 and 25 respectively.

35 A wire 33 has jewels 34 threaded thereon and is clamped by the clamps 29 and 30, the wire being drawn taut by manipulation of the nut 28.

Adjustable rests 35 and 36 are provided at each 40 side of the rotating brush and have a curved bearing surface 37 having approximately the same curvature as the rotating brush to receive and support the ends of the jewel carrying wire 33. The rest 36 is pivoted to a link member 38 at 39 intermediate of its length and to link member 40 at 41. The link member 40 is pivotally supported at 42 on the support 3 and carries an adjusting screw 43 which is threaded into an extension 44 and is fixedly and rotatably held at 45 the base 1. The movement of the rests 35 and 36 is such that the supporting surface is always parallel or concentric with the curvature of the brush. This provides very accurate individual adjustment of the rest 36 with relation to the 50 surface of the rotating brush. The rest 35 is 55

supported in a like manner and adjusted by adjusting screw 45 to give that rest individual adjustment.

In operation the wire 33 is charged with diamond dust in the well known manner by rolling the relative soft iron or copper wire on a steel plate in a mixture of diamond dust and while using a steel bar to press the material into the surface of the wire. This is a hand operation and is a normal method used to charge wire with diamond dust. The jewels 34 are then strung on the wire in a number limited only by the desire of the operator and the size of the brush being used. The wire is clamped in the clamp 29 and stretched taut to the clamp 30 by hand, the nut 28 being tightened on the threaded rod 27 to bring the wire to the desired tautness. The rests 35 and 36 are adjusted to such a position that they support the jewels in brushing contact with the brass bristles of the rotating brush so that the jewels are rotated on the charged wire, the bristles not only giving the jewels rotation but also lateral movement causing the internal bore of the jewels to be oiled. This lateral movement is accomplished by a slight canting of the abrading wire on which the jewels are carried. This slight canting causes the jewels to move from one end of the wire to the other as the wire is never more than half filled with jewels. Thus a lateral movement is given to the jewels by the rotating brush simultaneously with the rotating movement, the lateral motion on the wire serving to prevent wearing of the wire in any one particular spot. The operator by grasping the rod 20 can now move the entire jewel mounting on the ball 13 so that the motion of the jewels is accelerated, the jewels working themselves toward the high side of the wire, which is of course, shifted from side to side by movement of the jewel mounting; in this manner the jewels are worked both ways across the length of the wire, are giving rotation and lateral movement by means of the rotating brush, the final result being that the internal bore of the jewel is rounded at the ends, this rounding being commonly termed by jewel makers as "oliving."

With the apparatus herewith described it is possible to produce a group of jewels in which the oliving is very nearly identical. With the method now being used where a single jewel is oiled by an operator it is very difficult to produce jewels having uniform oliving. It must be borne in mind that these jewels are extremely small, being of a size corresponding to the head of an ordinary pin, some being smaller and some larger and the almost impossibility of measuring this oliving when handling the jewels individually. This oliving operation which formerly required from 10 to 20 seconds on an individual jewel is now carried out on as many as 200 jewels at a time in approximately 30 seconds.

What we claim is:

1. A jewel oliving machine comprising an abrading wire supporting a plurality of said jewels, a rotating member, means supporting said abrading wire in close proximity to said rotating member as to bring the wire supported jewels in contact with the rotating member imparting rotation to the jewels, said abrading wire being movable to cause said rotating member to simultaneously give said jewels a lateral fluttering motion along the length of the abrading wire to round out the inner bore of the jewels.

2. A jewel oliving machine comprising an abrading wire supporting a plurality of said jew-

els, a rotatable brush, means supporting said abrading wire and jewels in close proximity to said rotating brush, said abrading wire being movable to cause the brush to impart both rotation and lateral fluttering motion along the length of said wire to said jewels.

3. A jewel oliving machine comprising a base, a rotatable brush mounted on said base, an abrading wire supporting a plurality of jewels, and means for universally supporting said abrading wire to permit said abrading wire to be brought into jewel contacting brush position at any relative desired angle to said brush.

4. A jewel oliving machine comprising a base, a pair of standards mounted on said base, a brush journaled in said standards, means for rotating said brush, an abrading wire supporting a plurality of jewels, means for supporting said abrading wire bringing the jewels into brush contacting position, means supported by said standards to limit the position of said jewel carrying wire.

5. A jewel oliving machine comprising a base, a pair of standards mounted on said base, a rotatable brush journaled in said standards, means for rotating said brush, an abrading wire supporting a plurality of jewels, means for supporting said abrading wire to bring the jewels into brush contacting position, and means for adjusting the tension on said abrading wire.

6. A jewel oliving machine comprising a base, a brush mounted for rotation on said base, an abrading wire supporting a plurality of jewels, means for universally supporting said abrading wire on said base to permit adjustment of the wire relative to the brush both as to its distance from the brush and its relative angle with the brush and means for limiting the position of said wire with regard to the brush.

7. A jewel oliving machine comprising a base, a brush mounted for rotation on said base, an abrading wire supporting a plurality of jewels, means for supporting said wire in close proximity to said rotating brush, means carried at each side of the rotating brush to limit the position of said wire with regard to said brush, and individual adjusting means for said limiting means.

8. A jewel oliving machine comprising a base, a pair of standards mounted on said base, a brush journaled for rotation in said standards, means for rotating said brush, a ball carried by said base, an adjustable clamp universally mounted on said ball, an abrading wire supporting a plurality of jewels carried by said clamp and means for adjusting said clamp to permit the wire to be held in any desired position relative to said rotating brush.

9. A jewel oliving machine comprising a base, a pair of standards mounted on said base, a rotatable brush mounted in said standards, an abrading wire supporting a plurality of jewels, means for adjusting the tension of said wire, means for universally supporting said tension adjusting means in close proximity to said rotating brush, means for limiting the position of said wire with regard to said brush and means for adjusting said limiting means to permit the jewels mounted on said wire to be brought into contact with the ends of the bristles of said brush, said abrading wire being movable to a position to cause said brush to impart both rotation and lateral fluttering movement along the length of the wire to said jewels.
